RAIL TIE AND FASTENING MEANS

John K. Wedgworth, York, Ala.

Application October 26, 1945, Serial No. 624,754

3 Claims. (Cl. 238—275)

1

The invention aims to improve upon the construction shown in my U. S. Patent No. 1,436,839 of November 28, 1922, primarily by providing a novel construction to readily permit the use of a prying tool for upwardly bending the detents of the tie from engagement with the tie-contained blocks when said detents are to be upwardly bent to released position.

A further object is to provide an improved construction which will not interfere with the necessary yielding of the rails during passage of a car or train along the same.

Figure 1 of the accompanying drawing is a sectional perspective view showing the improved construction and the manner of using the prying tool.

Fig. 2 is a vertical sectional view showing the prying tool in use.

Fig. 3 is a sectional view on line 3—3 of Fig. 2.

Fig. 4 is a perspective view of one of the tie-contained blocks.

In the drawing above briefly described, the numeral 5 denotes a hollow metal tie having a longitudinal slot 6 in its top 7. Within the tie 5 are two metal blocks 8 each having a rail-engaging finger 9 extending through the slot 6. The upper side of each block 8 is formed with upwardly open recesses 10 providing shoulders 11 facing away from the rail 12, and the tie top 7 is provided with downwardly bent detents 13 received in said recesses 10, said detents having end surfaces facing toward the rail and abutting said shoulders to secure the block in place.

The construction so far described finds its equivalent, if not its duplicate, in the patent above referred to. I improve upon the patented construction, however, in ways described below.

Each block 8 is provided with an upwardly open recess 14 which is exposed at the slot 6 and extends under the detents 13, permitting the insertion of a T-head 15 under both detents 13 when they are to be upwardly bent to released position. I also provide each block with a fulcrum 16 for the shank 17 of the prying tool, said fulcrum being disposed at the side of the recess 14 remote from the rail 12 and being exposed at the slot 6.

The T-head 15 may readily be inserted (see dotted lines of Fig. 3) and positioned under both detents 13, and the shank 17 engaged with the fulcrum 16, whereupon the tool may be readily used to upwardly bend said detents simultaneously to released position, whenever the rail 12 is to be released for one reason or another.

It is preferred that the wall 18 of each recess

2

14, toward the rail 12, be in the same vertical plane with the shoulders 11, whereby portions of the end surfaces of the detents 13 will abut said shoulders, and other portions of said end surfaces will abut portions of said wall 18. Even though the detents are bent downwardly as shown, this downward bending is not sufficient to prevent them from abutting the shoulders 11 and wall 18, said bending being only a trifle more than the thickness of the metal.

In the preferred construction of the improved tie and rail fastening means, the lower side 19 of each finger 9 is rounded to give it a transversely convex form, preventing it from interfering with vertical yielding of the rail 12 during passage of a car or train along the track.

From the foregoing, taken in connection with the accompanying drawing, it will be seen that novel and advantageous provision has been made for attaining the desired ends, and while preferences have been disclosed, minor variations may be made.

The prying tool is preferably so constructed that it may be used not only for upwardly prying the detents 13, but may be employed also as a spike puller, a pinch-bar, and a crow bar.

I claim:

1. In a rail supporting and clamping means embodying a hollow metal tie having a longitudinal slot in its top, and a block within said tie having rail-engaging means extending through said slot, said tie top having a downwardly bent detent at one side of said slot and engaging said block to secure it in place; said block being provided with an upwardly open recess exposed at said slot and extending under said downwardly bent detent to permit insertion of a prying tool under said detent when it is to be upwardly bent to released position, said block having a fulcrum for said prying tool located at one side of said recess and exposed at said slot.

2. In a rail supporting and clamping means embodying a hollow metal tie having a longitudinal slot in its top, and a block within said tie having rail-engaging means extending through said slot, said tie top having two downwardly bent detents at opposite sides of said slot and engaging said block to secure it in place; said block being provided with an upwardly open excess exposed at said slot and extending under both of said detents to permit insertion of a T-headed prying tool under said detents when they are to be bent upwardly to released position, said block having a fulcrum for said prying tool lo-

cated at one side of said recess and exposed at said slot.

3. A structure as specified in claim 2; said detents having end surfaces facing toward the rail, said block having vertical shoulders facing away from the rail and abutting portions of said end surfaces of said detents, one wall of said recess being in the same vertical plane with said shoulders and abutting other portions of said end surfaces of said detents.

JOHN K. WEDGWORTH.
